UNITED STATES PATENT OFFICE.

CHRISTOPHER S. BENJAMIN, OF LINCOLN, NEBRASKA, ASSIGNOR OF ONE-HALF HIS RIGHT TO GEORGE P. TUCKER, OF SAME PLACE.

IMPROVEMENT IN MITERING-MACHINES.

Specification forming part of Letters Patent No. 172,955, dated February 1, 1876; application filed July 10, 1875.

To all whom it may concern:

Be it known that I, CHRISTOPHER S. BENJAMIN, of Lincoln, in the county of Lancaster and State of Nebraska, have invented a new and valuable Improvement in Mitering-Machines; and I do hereby declare that the following is a full, clear, and exact description of the construction and operation of the same, reference being had to the annexed drawings making a part of this specification, and to the letters and figures of reference marked thereon.

Figure 1 of the drawings is a representation of a plan view of my mitering-machine. Fig. 2 is a longitudinal vertical sectional view of the same, and Fig. 3 is a front view thereof.

The nature of my invention consists in a revolving bed-plate, secured to a table or bench in such manner as to admit of the machine being turned to the right or left, and containing a rocking frame that supports the standards and sliding saw-guides.

My invention further consists in the work-clamps and in the combination of parts, as will be hereinafter more fully set forth.

In the accompanying drawings, A represents the slotted circular base, attached to a suitable base-plate, through the center of which passes a bolt, for pivoting the machine to a bench or table, and allow of the machine being rotated in either direction. On bearings *a* in the base A rests a frame, B, which is allowed to rock to either side. On this frame is a vertically-slotted stationary standard, C, and a similar standard, C', is made movable in a longitudinal slot in the frame, and fastened at any point desired by set-screws. In place of slotted standards, two parallel standards may be used, in each case their upper ends being connected by a cap hinged at one end, and fastened at the other end by a set-screw. In each standard, or between each pair of standards, is placed a sliding saw-guide, E, slotted to receive the saw-blade. On the standards are adjustable stops *e*, to stop the downward movement of the saw-guides at any point, and thereby prevent the edge of the saw from coming in contact with the iron-work of the machine. By tilting the frame B, the standards and saw-guides

are inclined to any desired angle with the bed-plate, for sawing splayed work, and the frame may be held at the desired angle by suitable set-screws. H represents the frame of the clamp pivoted at *i*, near the center, and may be adjusted at any angle from said point, and held by a bolt, *f*, working in the slot in the base. In this frame is a screw, I, which works in a female screw through the movable jaw J, and works loose through another movable jaw, J', and upon the end of the screw is a nut, *h*, held stationary, or rather kept from turning with the screw by any suitable means, so that by turning the screw I the jaws J J' will traverse back and forward equidistant from each other. To increase or diminish the space between the jaws the nut *h* must be unlocked, and then run out or in as required, making the space in the clamp to correspond to the width of the molding required. Two of these clamps are used, one on each side of the frame B, and they are adjusted at any desired angle to each other. Two moldings being held by the two clamps, the saw is passed through at the junction of the two pieces. After the saw has cut through, the moldings are forced together at the joint by turning each screw I to the right, and drawn apart by reversing the screws. When the joints are apart the ends may be glued, and then forced together and held firmly until further secured with screws or dowels. The right-hand clamp is provided with a gage for the purpose of cutting the moldings to the proper length, which is done by the first joint or miter on the left-hand jaw. On the right-hand jaw J' is formed a socket, *m*, in which a rod, L, is inserted and held by a set-screw, *n*, and on this rod is a collar, P, provided with a pin, *s*, and fastened by a set-screw, *t*. The gage L P is set to the required length of the molding at the inner edge. The molding is then placed in the right-hand clamp, the inner corner against the gage-tooth *s*, the other end under the saw, which cuts it to the proper length, and the process continued until the requisite number of pieces are cut.

What I claim as new, and desire to secure by Letters Patent, is—

1. The combination, with the adjustable

clamp of the mitering machine herein described, of the socket *m*, rod *L*, set-screw *n*, and collar *P*, provided with a pin, *s*, and set-screw, *t*, substantially as and for the purpose set forth.

2. The combination, with the circular slotted bed-plate and saw-frame, of the work-clamps having the adjustable jaws *J J'*, screw *I*, wrench-nut *h*, and a gage, *L P*, attached to

one of said clamps, substantially as described, and for the purpose set forth.

In testimony that I claim the above I have hereunto subscribed my name in the presence of two witnesses.

CHRISTOPHER S. BENJAMIN.
